CLAIM

The ornamental design for a clasp for a bag, as shown and described.

DESCRIPTION

1. Clasp for a bag

1.1 : Perspective

1.2 : Front

1.3 : Back

1.4 : Right

1.5 : Left

1.6 : Top

1.7 : Bottom

1.8 : Perspective

In the drawings the dashed lines represent items which form no part of the design and are not claimed; reproduction 1.8 shows the clasp in the open condition.
